ATTORNEY

UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC FURNACE.

Application filed September 23, 1921. Serial No. 502,691.

To all whom it may concern:

Be it known that I, ORA A. COLBY, a citizen of the United States, and a resident of Irwin, in the county of Westmoreland and State of Pennsylvania, have invented a new and useful Improvement in Electric Furnaces, of which the following is a specification.

My invention relates to electric furnaces and particularly to electric-resistance furnaces, and it has for its object to provide a relatively simple and quickly mountable and demountable resistor for an electric-resistance furnace.

In practising my invention, I provide a relatively heavy resistor member, substantially of rod or bar form, having a plurality of spaced integral flattened portions. I provide refractory supporting members located in spaced relation in the walls of the furnace chamber, the said members having recesses which permit of initially locating the resistor member therein, with the main portions lying in the recess, the resistor member being then moved longitudinally thereof to cause the flattened portions to lie in the recesses to support the resistor member.

In the single sheet of drawings,

Figure 1 is a view, in vertical lateral cross-section, of an electric furnace comprising the device embodying my invention;

Fig. 2 is a longitudinal sectional view on the line II--II of Fig. 1;

Fig. 3 is a fragmentary view, in plan, of a resistor member conforming to my invention, and

Fig. 4 is a view, in side elevation, of the portion of a resistor member illustrated in Fig. 3.

An electric furnace 10 comprises a metallic framework or casing 11 having a plurality of supporting members 12 suitably secured thereto. The bottom wall 13 and side walls 14 are suitably spaced apart in the framework 11 and co-operate with an arched roof 15 to form a furnace chamber 16 of any suitable or desired contour and dimensions. The walls 13 and 14 and the roof 15 may be made of blocks or bricks of any suitable non-heat-conducting material employed in the art. An inner lining 17 of suitably shaped bricks or blocks, made of any high-temperature-resisting material usu-

ally employed for such purposes may be provided.

A plurality of resistor-supporting means 18 are located at spaced intervals longitudinally of the furnace walls and comprise either an integral member of substantially the same height as the furnace chamber, or, as illustrated in the drawing, a plurality of bricks or blocks, substantially of T-shape. The bricks or blocks in the inner lining immediately adjacent the members 18 are suitably shaped to provide a slot 19, also substantially of T-shape, to receive the members 18. The bricks or blocks in the outer walls 14 immediately adjacent the members 18 are easily removable to permit of quick and easy removal and replacement of the members 18 whenever this becomes necessary.

If the resistor-supporting means 18 comprises an integral block, it is provided with a plurality of spaced laterally extending recesses 20, substantially of T-shape, to permit of locating therein a resistor to be described hereinafter more in detail. If the resistor-supporting means 18 comprises a number of bricks or blocks, suitable recesses 20 are located in each block, immediately adjacent the inner face at the sides thereof, that the combined recesses, when the bricks are located in proper operative positions relatively to each other in the furnace wall, will constitute slots of substantially T-shape. The resistor-supporting means 18 located in the roof of the furnace is of substantially the same construction as hereinbefore described in connection with the side walls of the furnace, except that they are so shaped, either as an integral member or as a plurality of blocks, as to conform to the shape of the roof, which is here illustrated as an arch, although this is not essential.

A resistor member 21 comprises an elongated rod, bar or tube of suitable resistance material and of relatively large lateral area of cross section. A plurality of spaced, integral, flattened auxiliary portions 22 are provided in the resistor member, each of relatively short length, the main portions of the resistor member being of an original predetermined shape or contour of lateral cross section. The flattened portions 22 may be formed in any desired manner, as by roll-

ing between two co-operating rolls or by pressing between dies to change the lateral contour without substantially changing the area of cross section thereof. The resistor is bent into substantially the form illustrated in Fig. 2 to comprise a plurality of substantially parallel-extending straight portions having integral end connections with the flattened portions located symmetrically in each of the straight portions.

The method of mounting the resistor member in the furnace chamber is as follows, it being assumed that it is desired to mount a resistor member in the right-hand wall of the furnace illustrated in Fig. 1. A resistor member 21, comprising four convolutions, is so located that portions of the individual convolutions are located in the grooves or recesses 20, it being understood that, initially, the resistor member is temporarily placed in the furnace longitudinally displaced a short distance from its normal operative position relatively to the supporting means 18. After all of the convolutions have been located in the recesses or grooves 20, the resistor member is moved, a short distance, in a longitudinal direction until the auxiliary portions 22 lie in the recesses 20 and engage other portions thereof than were engaged before by the main portions of the resistor member. The same description applies to the method of mounting a resistor in the other wall or in the roof of the furnace, it being evident that, as the flattened portions 22 of the resistor member 21 engage the overhanging flange of the recesses 20 the resistor member 21 is held securely in its operative position in the furnace.

As hereinbefore stated, the resistor is made sufficiently large in lateral cross section to permit of its being substantially self-supporting between the members 18, which may, of course, be spaced apart a greater or a lesser distance as may be required.

It may be noted that the device embodying my invention provides a relatively simple and easily manufactured resistor member which is made of relatively heavy and substantially self-supporting material requiring only a relatively simple supporting means and which may be quickly and easily mounted in and dismounted from its operative position in the furnace chamber.

This application is closely related to my co-pending application, Serial No. 523,212, filed December 17, 1921, and to an application of T. A. Baird, Serial No. 529,004, filed January 13, 1922, both applications being assigned to the Westinghouse Electric & Manufacturing Company.

Various modifications may be made in the device embodying my invention without departing from the spirit and scope thereof, and I desire that only such limitations shall

be placed thereon as are imposed by the prior art or are specifically set forth in the appended claims.

I claim as my invention:

1. An electric furnace comprising a resistor rod having a plurality of symmetrically spaced integral flattened portions.

2. An electric furnace comprising a supporting means and a resistor rod having a plurality of integral flattened portions located in said supporting means.

3. An electric furnace comprising spaced supporting means and a resistor rod having a plurality of integral flattened portions, said supporting means being engaged by said flattened portions only.

4. An electric furnace comprising spaced supporting means and a resistor rod having a plurality of integral flattened portions engaging said supporting means, said rod being substantially self-supporting between said supporting means.

5. An electric furnace comprising a resistor member having a predetermined contour of lateral cross-section in its main portions and integral auxiliary portions of different contour and of substantially equal area.

6. In an electric furnace, in combination, a resistor member having relatively long main portions of predetermined contour and integral auxiliary short portions of different contour, and a supporting means for said resistor having a plurality of recesses therein for initially receiving parts of the main portions of said resistor and for permanently receiving said auxiliary short portions to hold said resistor in its operative position in said furnace.

7. An electric furnace comprising a resistor member having recurrent consecutive integral portions of different shape in lateral cross-section.

8. An electric furnace comprising a resistor member having recurrent consecutive integral portions of different contour in lateral cross-section and of substantially equal cross-sectional area.

9. In an electric furnace, in combination, a resistor member of predetermined contour of lateral cross-section having a plurality of substantially parallel-extending end-connected convolutions, each convolution having a plurality of integral relatively short auxiliary portions of different contour and a supporting means for said resistor having recesses therein for operatively engaging said short auxiliary portions of the resistor convolutions to maintain said resistor in its operative position in said furnace.

10. In an electric furnace, in combination, a resistor member of predetermined contour of lateral cross-section having a plurality of substantially parallel-extending end-connected convolutions, each convolution hav-

- ing a plurality of integral relatively short auxiliary portions of different contour, and a plurality of spaced relatively narrow refractory supporting means, each of said means having a plurality of lateral recesses therein of such form as to permit of initially engaging the main portions of said convolutions and finally engaging the auxiliary portions thereof for maintaining said resistor member in its operative position in said furnace.
11. In an electric furnace, in combination, a resistor member having main portions of a predetermined contour of lateral cross-section and spaced integral auxiliary short portions of different contour and spaced refractory supporting means for said resistor member having recesses therein for permitting the initial engagement of the main portions of said resistor with said supporting means and the final engagement of the auxiliary portions of said resistor with said sup-
- porting means, the resistor member being self-supporting between said refractory supporting means. 25
12. In an electric furnace, in combination, a resistor member having main portions of a predetermined contour of lateral cross-section and spaced integral auxiliary short portions of different contour and spaced refractory supporting means for said resistor member having recesses therein for permitting the initial engagement of the main portion of said resistor with said supporting means for permitting the longitudinal displacement of said resistor member relatively to said supporting means to maintain the resistor member in final engagement therewith. 30
13. In an electric furnace, in combination, a resistor member having main portions of a predetermined contour of lateral cross-section and spaced integral auxiliary short portions of different contour and spaced refractory supporting means for said resistor member having recesses therein for permitting the initial engagement of the main portion of said resistor with said supporting means for permitting the longitudinal displacement of said resistor member relatively to said supporting means to maintain the resistor member in final engagement therewith. 35

In testimony whereof, I have hereunto subscribed my name this 19th day of September, 1921.

ORA A. COLBY.
